UNITED STATES PATENT OFFICE.

GARRETT SLATER, OF KALAMAZOO, MICHIGAN.

VEHICLE-HEATER AND STREET-LIGHTER.

SPECIFICATION forming part of Letters Patent No. 634,674, dated October 10, 1899.

Application filed March 6, 1899. Serial No. 707,990. (No model.)

To all whom it may concern:

Be it known that I, GARRETT SLATER, a citizen of the United States, residing at Kalamazoo, in the county of Kalamazoo, State of Michigan, have invented a new and useful 5 Vehicle-Heater and Street-Lighter, of which the following is a specification.

My invention relates to heaters which are intended for attachment to the floor or bottom of vehicle-bodies, pendent beneath the same, and open into the body through the floor in a manner to admit the heat beneath the feet of the occupants of the vehicle.

The object of my invention is to construct 15 a simple and cheap device which can be easily filled, cleaned, and cared for, the oil-holding part being detachable from the body of the heater and the chimney and body made in a manner that light will be thrown from beneath the vehicle out each side, front, and rear of said vehicle, as well as furnishing the heat for the comfort of the occupants.

A construction embodying my invention is described below and pointed out in the 25 claims.

In the accompanying drawings, forming a part of this specification, Figure 1 is an elevation of the heater and lighter complete; Fig. 2, a sectional elevation on lines *e e* and *c c* in Figs. 3 and 4, showing the interior; Fig. 3, a plan of Fig. 1; Fig. 4, a section on line *a a* in Figs. 1 and 2, looking from a point above; Fig. 5, a section on line *v v* in Fig. 2, looking from a point at the left and showing 30 a broken portion of the wick-tube in elevation and detached from the heater; Fig. 6, an elevation of a broken wick and showing means of raising it, said figure being enlarged; Fig. 7, a section on line *s s* in Fig. 2, looking 35 from a point above and showing the wick-raising lever broken; and Fig. 8 is a dotted elevation of a vehicle-body, showing the position the heater and lighter occupies when in use.

40 The lighter and heater is hung in a hole through the floor 9 of the vehicle-body. The vehicle of course may be a cutter, sleigh, buggy, or car, or anything in which people ride. Fig. 8 shows a dotted vehicle-body and 45 the position the heater and lighter is to oc-

cupy between the seat and dashboard, but beneath the floor 9. This floor 9 in Figs. 1, 2, and 3 is shown broken.

The body 12 of the heater and lighter has a flanged overtop 13, resting on the floor 9, 55 and is screwed down on said floor, as in Figs. 2 and 3. The body 12 has four bull's-eyes 14, 15, 16, and 17, one on each of four sides, to let the light shine through, as explained farther on. This body 12 also has a row of 60 holes 18 through it on about a level with the top of the wick 19 to let in air and a row of holes through the wall near the top and beneath the vehicle-floor, through which the bad fumes of the burning oil escape. These 65 holes are shown at 20. The flanged overtop 13 referred to has holes 21, leading into the vehicle-body, for the escape of the heat from the heater and lighter.

The oil-holding part 22 of the device has a 70 circular depression in the top at 23, bounding a central hole 24 through said part 22, said depression being bounded by the walls 25, 26, and 27, the latter being a floor to said depression, Fig. 2. Beneath the inner edge of this 75 floor-wall 27 is a circular wall 28, extending to the bottom of the oil-holding part 22. These walls 25, 26, 27, and 28 are all integral with each other. The wall 25 at two opposite points, as in Fig. 2, has an indentation formed 80 therein, making thereby a shoulder or catch 29. The lower end of the body 12 of the device sits detachably in the depression 23 near the wall 25, as in Fig. 2. At the points where the shoulders 29 are located are springs 30, 85 which are attached to the wall of the body 12. In these springs 30 are formed shoulders 31 for catching under the shoulders 29 of the wall 25. These springs 30 from their shoulders 31 pass into the wall of the body 12 through a 90 hole in said wall and thence a short distance upward and thence outward through a hole in the wall of the body 12 and terminate in a turned-up end 32 for pressing the finger against to force the springs 30 inward and disconnect their shoulders from the shoulders 29, when the oil-holding part 22 can be lowered, and thus disconnected from the body 12 of the heater and lighter. Thus the springs 30 remain with the body 12, and the part 22 95 100

is conveniently detached from said body and no openings are made in the part 22, causing it to leak oil.

A tube 33 extends from a point approximately on a level with the row of holes 18 of the body 12 to the bottom of the oil-holding part 22 and constitutes the inner wall of the wick-tube, while the walls 26 and 28 of the part 22 constitute the outer wall of the wick-tube. The wick-tube is thus circular in form, Figs. 4 and 5. The wall 28 has a series of holes through it (shown by character 34, Figs. 2 and 5) to supply the wick 19 with oil from the interior of part 22. The wick 19 is circular or tubular in form like the wick-tube, Figs. 4 and 6. A band 25 surrounds the lower end of the wick 19, and upward from this band project a series of prongs 56, the upper ends of which prongs engage the wick when raising it, Fig. 6. This feature is quite similar to those in use; but I have a means connected with it which enables one to raise the wick from a point above—as, for instance, by a person in the vehicle. It consists of an arm 36, attached to the band 25 and extending outward through a vertical slot 37 in the wall 28. The arm 36 moves up and down in said slot when raising and lowering the wick, Figs. 2 and 6. A plan of the arm 36 is shown broken in Fig. 7. In Fig. 1 is an upright shaft 38, the lower end of which is made in the form of a screw 39, which screw passes into a hole in the end of the wick-raising arm 36. Turning this shaft 38 one way and the other raises the arm 36 or lowers it, as the case may be, and hence raises or lowers the wick 19. The upper end of the shaft 38 is in one of the heat-escaping holes in the plate 13, and the shaft has a ring 40 in the upper end. When said ring is down in the hole, to which location it may be tilted, it is out of the way, but by raising it to the position in Fig. 2 with the thumb and finger it is used to turn the shaft 38. This shaft passes through a little tube 41 projecting upward from the floor-wall 27, to which said tube is attached. As this tube 41 is as high or a little higher than the upper surface of the oil the oil which enters the tube cannot escape.

The chimney consists of two concentric tubes, the lower end of which chimney surrounds the upper portion of the wick-tube proper and extends thence upward to a point just above the upper boundary of the bull's-eyes 14, 15, 16, and 17 of the body 12. The outer one 57 of the concentric tubes detachably rests upon the floor-wall 27 of the depression 23 of the oil-holding part 22 and has an offset 42, which brings the portion surrounding the wick-tube close to said tube. The inner one 43 of the concentric chimney-tubes detachably rests upon a ledge 44 on the inner surface of the inner wall of the wick-tube, Figs. 2 and 4. Fig. 2 shows the ledge. The inner tube 43 also has an offset, which brings the lower portion close to the inner

wall of the wick-tube. (See 45 in Figs. 2 and 4.) By this means the upper portion of the chimney above the flame is larger than the lower portion and gives the flame 46 proper room. In the inner tube 43, and thus being in the vertical central hole 24 leading through the wick-tube and chimney, are two partitions 47 and 48, one above the other, Figs. 2 and 4. These partitions have a hole through them to allow the air to pass through, but still retard said air, as compared to the effect if the partitions were not used, and in many cases no doubt the partitions need not be used. The chimney-tubes have holes 49 through them near the flame 46 and the upper end of the wick-tube to furnish air to the flame. In some instances I have found it desirable to supply the chimney-tubes throughout with like holes 50, Fig. 2, and for the same purpose; but this may be a matter of choice or governed by the apparent needs.

The outer chimney-tube 57 is provided with windows 51 of glass or mica or some transparent material which will allow the light to shine through. There is one opposite each bull's-eye 14, 15, 16, and 17, and thus the light shines through the glass 52 of the bull's-eyes. The light thus shines on both sides of the street or track or surface which the vehicle is traversing, also behind, and, what is very important, directly on the street beneath the horse (when one or more are used) from the rear forward. Thus the whole territory occupied by the vehicle and team, and beyond said territory even, is lighted up by a light near to it coming from beneath the vehicle, which is very desirable for the driver, besides at the same time the occupants of the vehicle are kept warm.

When removing the oil-holding part 22 from the body 12 for the purpose of examination, filling with oil, or trimming or changing the wick, &c., the wick-tube, chimney, and wick-raising apparatus all come out with it, and this fact and the detachability of the chimney-tubes make it all very convenient to manage. Of course as the catch-springs are attached to the closure-wall of the body 12 they remain with said body when the oil-holding part 22 is detached. Should this part 22 be set down on the ground, it rests on the bottom projections 53, and thus will not prevent the air from passing up into the hole 24 and smother the light.

Having thus described my invention, what I claim as new, and desire to secure by Letters Patent of the United States, is—

1. The combination of a vehicle-body, the body of the heater and lighter pendent from beneath said body, the oil-holding part having the upper central walled-up depression, with the lower end of the heater-body attached in said depression, the upright tube in the depression and communicating with the oil-chamber, the wick-tubes, a band for surrounding the wick and bearing the prongs

- for engaging the wick, the lateral arm attached to and extending horizontally from the band and provided with a hole in its outer end, a vertical shaft passing loosely through the upright tube and having its upper end accessible within the vehicle-body, and its lower end being in the form of a screw and passing through said hole in the end of the lateral arm, substantially as set forth.
- 5 2. The combination of the heater and lighter body, an oil-holding part having the upper central walled-up depression, in which the lower end of the heater-body is detachably attached, the concentric wick-tubes, the inner 10 one of which is provided with a ledge on its inner surface, the concentric chimney-tubes, the lower end of the inner one detachably resting on said ledge of the inner wick-tube and having an offset bringing it near the inner wick-tube, the outer chimney-tube detachably resting on the floor of the central depression and having an offset bringing it near the outer wick-tube, whereby the oil-holding part of the heater and lighter, together with its wick-tubes is detachable from the pendent body of the heater and lighter and the chimney-tubes are detachable from the oil-holding part, substantially as set forth.
- 15 3. The combination of the body of a vehicle, the body of the heater and lighter pendent
- from beneath said vehicle-body, the lighting and heating portion of the device being enclosed within the heater-body and having an oil-holding part provided with the central walled-up depression within which the lower 20 end of the heater-body is detachably attached, said heater-body having in its wall-closure a bull's-eye at each side and one at the front and one at the rear, a wick-tube provided on its inner surface with the ledge, the concentric chimney-tubes, the lower end of the inner one detachably resting on said ledge of the wick-tube, the outer chimney-tube detachably resting on the floor of said depression and being provided, in its opaque closure, 25 with a transparent part at each side and in front and in the rear, said transparent parts registering with the bull's-eyes in the wall-closure of the heater-body, whereby the light and its windowed opaque chimney are entirely inclosed and said light is concentrated in the four directions only beneath the vehicle-body, substantially as set forth.
- 30 In testimony of the foregoing I have hereunto set my hand in the presence of two witnesses.

GARRETT SLATER.
